UNITED STATES PATENT OFFICE.

MALCOLM W. EDGAR, OF GROSSE POINTE, MICHIGAN.

BELT-FASTENER-ENGAGING TOOL.

1,185,186.

Specification of Letters Patent. Patented May 30, 1916.

Application filed April 18, 1913. Serial No. 762,149.

To all whom it may concern:

Be it known that I, MALCOLM W. EDGAR, a citizen of the United States of America, residing at Grosse Pointe, in the county of Wayne and State of Michigan, have invented certain new and useful Improvements in Belt-Fastener-Engaging Tools, of which the following is a specification, reference being had therein to the accompanying drawings.

10 The invention relates to belt fastening devices and has particular reference to the novel method of engaging the fasteners with the belt, and in the means employed for this purpose. In the present state of the art, a 15 form of belt fastener quite extensively used comprises a spaced series of hooked staples secured to each end of the belt so as to intermesh with each other, being pivotally connected by a central pin. For convenience 20 in shipment, the individual staples have been mounted on cards or in gangs secured to each other, and the number of hooks in each card or gang is generally sufficient for a belt of considerable width. In use, where 25 the fasteners are secured to a belt of lesser width than that of the card or gang, the remaining hooks are usually wasted. Moreover, if all of the hooks which are used are 30 engaged simultaneously with the belt, this operation is one requiring more power than can be applied through a hand tool and some form of power machine is necessary.

The present invention is designed to facilitate the attachment of the fasteners; 35 first, by forming gang units of a standard size, so selected as to be of no greater width than the minimum width of belts in common use; second, the number of hooks in each gang is restricted to be within the 40 power of a hand-operated closing tool; and third, the hooks are secured to each other by detachable ganging strips which are readily removable after the closing operation, but which nevertheless securely hold 45 the hooks in the gang prior to the closing operation.

My invention further comprises the means employed for engaging these gangs with the belt, which consists of a hand tool provided 50 with closing jaws and operating levers, and means for positioning the gang unit in the tool intermediate the jaws, also means for guiding the tool in the operation of placing a second gang so as to exactly aline the 55 same with the gang previously fastened.

Still further, the invention comprises a

construction of lever-operating mechanism for the tool, by which a very powerful final closing pressure may be given to securely fasten and embed the staple shanks in the 60 belt.

In the drawings: Figure 1 is a side elevation of a tool employed for closing the gang units in engagement with the belt; Fig. 2 is an end elevation partly in section; 65 Fig. 3 is a central section in a plane parallel to Fig. 1; Fig. 4 is a view similar to Fig. 1 showing a different adjustment of the parts; Fig. 5 is an elevation of a single gang unit secured to a belt of corresponding width; Fig. 6 shows a belt of greater width than a single unit, and illustrates the method of successively engaging the units and alining the same by the units previously engaged; and Fig. 7 is a perspective view of one of the gang units. 75

1 is my improved standard gang unit, which comprises a series of individual staples 2 having the sharpened, inwardly-extending hooks 3 at their opposite ends. 80 These hooks are relatively positioned by corrugated strips 4 engaging the same and secured from disengagement by adhesive cement. As above stated, the width of the gang is restricted to that of the minimum belt in common use, which necessitates the use of several units for the fastening of wider belts. All of these units must be accurately alined, as otherwise the pull of the belt would not be evenly distributed. I 90

have therefore devised a closing tool, which is capable of accurately positioning each unit with respect to the belt and the units previously engaged, and which also may be operated by hand with the requisite power,—the construction being as follows: A and B are hand-operated levers pivotally secured to each other by the pin O. C is a jaw fixed and preferably integral with the lever A, and C' is a co-operating paw pivoted to the jaw C by the pin M. To secure a powerful final pressure in the closing of the jaws C and C' and at the same time to provide sufficient movement, I have employed a toggle connection between the lever B and the jaw C'. This, as shown, comprises a portion on the lever B offset laterally from the pivot O to form one arm of the toggle, and this arm is connected by a link D engaging a pin P on the offset portion B' and a pin N connected to the jaw C'. The proportion of parts is such that when 105 110

the lever B is opened out from the lever A, the offset portion B' will be at an angle in relation to the link D to impart a maximum movement upon the initial closing of the 5 levers. When, however, the lever B approaches a position of parallelism to the lever A said offset portion is approaching its dead center, so that comparatively slight movement but great power is imparted to 10 the jaw C'.

To properly engage the units with the belt, the offset legs of each staple should be held in symmetrical relation to the plane of the belt, with all of the staples in proper 15 transverse alinement. I have therefore provided a unit holder E, which is pivoted upon the pin M, and is provided with slots E' for receiving the individual staples. There is also an aperture extending transversely of 20 the slotted portion for the reception of the pin G, which, when engaged, will hold the unit from disengagement but will permit a pivotal action upon the pin. The member E is also freely pivoted upon the pin M, and 25 may thus assume a medial position between the jaws C and C' in the various positions of angular adjustment thereof. As shown, 30 segmental wing extensions T may also be formed on the member E, these being provided with shoulders T' for engaging co-operating shoulders on the jaw members, as will be hereinafter set forth.

To drive the points of the staples into the belt, it is desirable to apply the maximum 35 pressure to the outer ends of the staple legs, and I have therefore provided bearing blocks F' and F², which are pivotally connected to the respective jaws C' and C by pins J' and J². These bearing blocks have 40 a limited freedom of movement upon their respective pins, and in initial position will assume an angular relation slightly different from that of the gang unit, so that the bearing will be upon the outer ends of the staple 45 legs. These bearing blocks may, if desired, be also provided with shoulders S for engaging the shoulders T' on the wings T to move the holder E into a central position when the jaws are fully open.

50 In operation, the unit to be secured is engaged with the tool by first opening the levers A and B and then inserting the staple ends in the slots E' of the member E, and placing the pin G in the transverse aperture 55 to lock the unit from disengagement. The belt is then inserted between the jaws and open hooks of the staples until its edge bears against the face of the member E. The levers A and B are then drawn together, 60 which may be accomplished by a single hand, in a similar manner to the operation of a pair of shears or pliers. The initial movement will force the sharpened points R of the staples into the leather which offers 65 but slight resistance to the movement. As

they become more deeply embedded the resistance increases but the power of the toggle is also increasing, and during its final movement is sufficient to not only force the points completely into the latter, but also to embed 70 the opposite legs into the opposite faces of the belt.

If the width of the belt corresponds to that of a single unit, the operation just described is complete, but where several units 75 are necessary they must be successively engaged and properly alined. The alinement is secured by forming the pin G of greater length than the width of the unit and the holding member E, and by inserting the 80 projecting end of this pin into the loops of the unit previously secured, as shown in Fig. 6. Thus the second unit will be exactly alined with the first one and each succeeding unit similarly alined until the entire width 85 of the belt is covered.

If desired, the tool may be provided with an adjustment to vary the relative positions of the jaws at the instant of application of a maximum force to the same. This provision 90 serves to better adapt the device for use with different thicknesses of belt, which, as shown, comprises an adjustment in the length of the link D. This link is provided with two or more apertures for receiving the 95 pivot pin N, which is detachable and is provided with a head I at one end and a winged nut H at the opposite end. Thus by shifting the point of engagement of the pin, the final 100 powerful movement of the toggle is adjusted for different thicknesses of belt. Such adjustment is not, however, absolutely essential, as the tool without adjustment will operate satisfactorily within the range of 105 variation of thickness of belts in common use. The lever A is preferably bifurcated to embrace the lever B and the link D while the jaw C' is bifurcated to embrace the jaw C and link D.

What I claim as my invention is:

1. A belt fastener engaging tool, comprising a pair of pivotally connected jaws, a holder for a gang unit of staples intermediate said jaws and pivoted to be independently movable in relation to each jaw, bearing blocks for said jaws arranged at such an angle to the holder as to initially bear upon the outer ends of the staples of the unit, and means for closing said jaws with progressively increasing power.

2. A belt fastener engaging tool, comprising a pair of pivotally connected jaws, a holder for a gang unit of staples pivoted to be independently movable with respect to said jaws intermediate the same, said holder being provided with a series of slots for the engagement of the individual staples of the unit and transversely apertured for the engagement of a securing pin, and a pin for engaging said transverse aperture and

of a length to engage the unit previously inserted to aline the subsequently fastened unit therewith.

3. A belt fastener engaging tool, comprising a pair of pivotally connected jaws, a pivoted holder for a gang unit of staples intermediate said jaws, means for closing said jaws upon said unit, and means for engaging a unit previously secured to aline 10 the unit in said holder therewith.

4. A belt fastener engaging tool, comprising a pair of pivotally connected jaws, a holder for a gang unit of staples secured by the same pivot to be independently movable 15 in relation to each of said jaws, bearing blocks pivotally connected to said jaws, and means for closing said jaws with progressively increasing power.

5. A belt fastener engaging tool, comprising a pair of pivotally connected jaws, one being bifurcated to embrace the other, a bifurcated lever connected with one of said jaws, a lever pivoted in said bifurcation, and a toggle connection between said second 25 lever and the other of said jaws.

6. A belt fastener engaging tool, comprising a pair of pivotally connected jaws, a holder for a gang unit of staples pivotally connected to said jaws and independently 30 movable in relation thereto, and means operating upon the spreading of said jaws for centering said holder.

7. A belt fastener engaging tool, comprising a pair of pivotally connected, lever-operated jaws, and a pivoted holder for a gang unit of staples intermediate said jaws and having its pivotal axis coincident with that 35 of the jaws.

8. A belt fastener engaging tool, comprising a pair of pivotally connected, lever-operated jaws, a pivoted holder for a gang unit of staples intermediate said jaws and having its pivotal axis coincident with that of the jaws, and means for temporarily 45 locking said unit in said holder.

9. A belt fastener engaging tool, comprising a pair of pivotally connected jaws, means for operating the same, and a pivoted holder for a gang unit of staples intermediate the jaws and having its pivotal axis coincident with that of the jaws.

10. A belt fastener engaging tool, comprising a pair of pivotally connected jaws, bearing blocks correlated with said jaws for 55 engaging a gang unit of staples arranged at an angle to initially bear upon the outer ends of the unit, and a holder for the gang unit intermediate said jaws, and maintained substantially centered relative to the jaws 60 through a connection with the bearing blocks.

11. A belt fastener engaging tool, comprising a pair of correlated jaws, bearing

blocks for said jaws arranged at an angle to initially bear upon the outer ends of the 65 staples of a gang unit, and a holder for the gang unit intermediate said jaws, and maintained substantially centered relative to the jaws through a connection with the bearing plates.

12. A belt fastener engaging tool, comprising a pair of correlated jaws, a pivoted holder for a gang unit intermediate said jaws, and bearing blocks respectively correlated with the jaws.

13. A belt fastener engaging tool comprising a pair of pivotally connected lever-operated jaws, of a pivoted holder for a gang unit intermediate said jaws, and bearing blocks respectively correlated with the jaws.

14. A belt fastener engaging tool, comprising a pair of correlated jaws, a holder for a gang unit intermediate said jaws, and bearing blocks respectively pivotally carried by the jaws.

15. A belt fastener engaging tool, comprising a pair of correlated jaws having bearing portions for engaging a gang unit of staples, one of said portions being pivotally carried by a correlated jaw, and a holder intermediate the jaws for engaging the gang unit.

16. A belt fastener engaging tool, comprising a pair of pivotally connected jaws, and a holder for a gang unit of staples intermediate said jaws and having a connection with the jaws arranged to maintain said holder substantially centered between the jaws when they are fully opened.

17. A belt fastener engaging tool, comprising a pair of pivotally connected jaws, a pivoted holder for a gang unit of staples correlated with the jaws intermediate the same, and means connecting the jaws and holder arranged to maintain the latter 105 substantially centered between the jaws when they are fully opened.

18. In a belt fastener, the combination with a pair of coacting jaws, of a pair of bearing plates mounted one upon each jaw 110 and movable relatively thereto, and a holder for a series of staples associated with said bearing plates.

19. In a belt fastener, the combination with a pair of coacting jaws, of a pair of bearing plates wholly supported one upon each jaw, angularly displaceable relatively to the jaws and actuatable by the jaws from an angular to a substantially parallel relation.

In testimony whereof I affix my signature in presence of two witnesses.

MALCOLM W. EDGAR.
